Des. 176,718
Patented Jan. 24, 1956

176,718

COMBINED TAPE RECORDER AND PLAYER

Kjell M. R. Gaarder, Stevensville, Mich., assignor to V-M Corporation, Benton Harbor, Mich., a corporation of Michigan

Application July 27, 1954, Serial No. 31,621

Term of patent 7 years

(Cl. D26—14)

FIG. 1

FIG. 2

Fig. 1 is a front perspective view of a combined tape recorder and player showing my new design with the cover removed;

Fig. 2 is an end view with the cover omitted; and

Fig. 3 is a front perspective view thereof in a closed position.

I claim:

The ornamental design for a combined tape recorder and player, as shown.
